UNITED STATES PATENT OFFICE

BARNEY GOLDMAN, OF NEW YORK, N. Y.

VENTILATING SYSTEM FOR PROJECTING ROOMS

Application filed April 5, 1930. Serial No. 441,770.

This invention relates to a ventilating system for projecting rooms and consists of an upwardly disposed chamber above the roof of the building, which connects with the projecting room below the chamber embodying a skylight having a plurality of gravitating sashes adapted to automatically open in case of excess heat inside the room. The invention also provides an automatic ventilating fan for supplying fresh air to the room and an exhaust fan to carry off the hot air and gases from the lamp of the projecting machine.

An object of the invention is to provide means whereby the excess heat generated by the projecting lamp is sucked out into the open air beyond the exterior of the skylight.

Another object of the invention is to provide flexible means between the lamp casing and the conduit leading to the suction blower, so as to compensate for any vibration caused by the projecting machine and the suction blower.

Another object of the invention is to provide automatic means whereby the foul air of the projecting room is forced out into the atmosphere and replaced by fresh air.

Another object of the invention is to provide manually operated means whereby all the gravitating sashes of the skylight may be opened simultaneously for ventilating purposes and automatic means for opening them in case of fire in the projecting room.

And still another object of the invention is to construct the same in units and provide means whereby it may be enlarged to accommodate any size projecting room and any number of projectors.

With these and other objects in view the invention resides more particularly in the novel combinations hereinafter described and claimed, reference being made to the accompanying drawings in which similar numerals of reference designate corresponding parts in all the views, in which:

Fig. 1 represents a vertical end elevation of my invention, mounted on top of the curb of a roof of a building, showing the projecting room and part of the curb in section.

Fig. 2 is a vertical side elevation of my

invention showing the position on the roof in relation to the projecting room which is shown in section.

Fig. 3 is a vertical cross-section on a larger scale, taken on line 3—3 of Fig. 4.

Fig. 4 is a vertical cross-section on line 4—4 of Fig. 3, and

Fig. 5 is a horizontal section on line 5—5 of Fig. 3.

The numeral 10 designates the projecting room, having a door 11. The room is formed or built of fireproof material and may be integral with the roof 12. Extending upwardly from the roof 12 and integral therewith is a curb 13 onto which is fastened the enclosure or ventilating apparatus 14 which is assembled from a number of units A—B—C and bolted together. Each section has at its inner ends vertically disposed and inwardly extending flanges 15 which are fastened together with bolts 16. The lower portion of the enclosure 14 has vertical end walls 17—18 and side walls 19. The side walls extend upwardly at an angle, forming a roof 20, terminating at the apex into an angular shaped flume 21. The end walls 17—18 extend straight upwardly and are fastened to the roof 20 and the ends of flume 21.

The side walls 19 have openings 22. Each opening is provided with a sash or cover 23. The lower portion thereof is hinged at 24 to the side walls 19. At each end of the opening 22 are outwardly extending triangular members 25 which are fastened to the slanting roof 26 thereby forming a hood or offset in the side walls 19. The triangular members 24 have their outer ends bent inwardly at 27 onto which the cover 23 fits tightly when closed.

By referring to Fig. 3, it will be seen that if the sash 23 is released, it will automatically uncover the opening 22 and drop downward to a position shown by dotted lines, and held in this position by a steel cable 28 which is fastened to the sash at one end and to the frame at the other.

The covers 23 are held in a closed position by a series of wire cables 29. These cables are fastened to the sash at 30 and each cable is equipped with a fuse link 31. The cable

passes over pulleys 32 and is fastened to a plate 33. To the lower end thereof is attached a chain 34 having a fuse link 31. The free end of the chain is fastened into a slit 35 of an angle iron 36 which is fastened near the roof 20 and extends downward within easy reach of the operator.

It will now be seen that if the chain 34 is released from its anchorage, the covers 23 will all open simultaneously, thereby ventilating the projecting room 10 and when the chain is again pulled down and fastened as before, all the covers will be closed. Now in case of fire in the projecting room, the flames will melt the lower or all the fuses thereby releasing all the sashes as before described.

By referring to Fig. 2, it will be seen that to the end wall 17 is fastened an electric fan 37 which extends into the enclosure and to the outside of wall 18 is attached a suction fan or blower 38.

The casing 39 of the electric fan 37 is fastened to the end wall 17 and extends into the enclosure 14 near the lower portion thereof. In front of the fan 37 and pivotally mounted in the casing 39 are a number of horizontally disposed slats 40 forming a shutter, which is normally closed on account of the slats being fulcrumed at their upper ends but will open when the current of air from the fan forces them outward. The object of this construction is so as to prevent weather and wind from entering the projecting room, when the fan is not running.

At the opposite wall 18 which is made hollow, and near the top thereof is fastened the fresh air intake 41 which consists of an inverted goose neck fastened to the outer side of the hollow wall. The air passes downward and out near the bottom of the inner side through outlets 42 into the enclosure. It will now be seen that when the fan 37 is started it will force the air from the projecting room 10 out into the open and fresh air will be drawn in through the inlet 41 thereby causing a circulation of fresh air throughout the projecting room. The outlets 42 may be extended downward towards the floor of the projecting room if necessary.

By referring to Figs. 1-2, it will be seen that the projecting apparatus 43 is mounted on the floor of the projecting room 10 and the projected rays pass through an opening 44 in the wall. This opening may also be protected against fire by an automatic shutter 45 mounted to slide in guides fastened to the wall. To the shutter is fastened a chain 46 having a fuse link 31. The free end of the chain may be fastened or anchored to any convenient place in reach of the operator. This arrangement is shown in Fig. 1.

To the vent pipe 47 of the projecting apparatus 43 is connected a flexible metallic hose 48 which extends upward some distance and

connects to a pipe 49 which extends upward and connects with flume 21. A pipe 50 connects the flume 21 with the suction end of the exhaust fan 38 which is located on the roof or some convenient place outside the enclosure 14 and is driven by an electric motor 52. The exhaust fan and motor are mounted on a base 53. The outlet 54 of the exhaust fan 51 delivers the exhaust into the open. The motor, of course, is controlled by the usual means.

It will now be seen that when the motor 52 is started, the exhaust fan 51 will suck the hot air gases generated by the lamp in the projecting apparatus through the flume 21 and connecting pipes, thereby causing a steady current of cool air to pass through the projecting apparatus thereby eliminating all danger of fire.

I claim:—

1. A ventilating system comprising a room having a projecting machine arranged therein, a skylight enclosure extending upwardly from the top of the room, a conduit located in the upper part of the skylight, a flexible tube connecting the conduit with the projecting machine, a blower mounted on the top of the room outside of the skylight communicating with the conduit to suck the heated air from the projecting machine to the exterior of the skylight, an inlet for conducting air into the room, gravity operated shutters normally closing a vent in the skylight, and a fan situated in the skylight for operating the shutters.

2. A ventilating system comprising a room having a projecting machine arranged therein, a skylight enclosure extending upwardly from the top of the room, gravity operated sashes coacting with the skylight, flexible members provided with fusible links connecting the sashes with the room, means for sucking the heated air from the projecting machine to the exterior of the skylight, and an inlet for conducting fresh air from the exterior of the skylight into the room.

Signed at New York, in the county of New York and State of New York, this 2nd day of April, A. D. 1930.

BARNEY GOLDMAN.
